Patented July 13, 1976

240,488

COMBINED BAR AND DISPLAY CABINET

Lawrence D. Taub, 7435 Boulevard East,
North Bergen, N.J. 07047

Filed Oct. 21, 1974, Ser. No. 516,785

Term of patent 14 years

Int. Cl. D6—04

U.S. Cl. D6—148

FIG. 1

FIG. 2

FIG. 3

FIG. 4

FIG. 1 is a front perspective view of a combined bar and display cabinet showing my new design with the doors in open position;

FIG. 2 is a front elevational view with the doors in closed position;

FIG. 3 is a right side elevational view; and

FIG. 4 is a rear elevational view.

The bottom of the combined bar and cabinet is similar to the top.

I claim:

The ornamental design for a combined bar and display cabinet, as shown and described.
